FIRING MECHANISM FOR AUTOMATIC FIREARMS

Václav Holek, Zabovresky, Brunn, Czechoslovakia,
assignor to Československá Zbrojovka, a. s.,
Brno, Brunn, Czechoslovakia, a Czechoslovakian company

Application July 14, 1937, Serial No. 153,653
In Czechoslovakia July 20, 1936

7 Claims. (Cl. 89—27)

This invention relates to firing mechanism for automatic firearms.

In known firing mechanisms the setting means for permitting the firing of single shots or a series of shots and the means for locking the firing mechanism are operated by means of separate levers, usually disposed laterally of the trigger. The defect of such a firing mechanism is not only its complicated construction, but also the difficulty of manipulation, which requires some considerable time for operating the members which are separated from one another, such as the trigger and the locking mechanism and the aforesaid setting means.

These defects are eliminated by the construction according to the invention, in which there is provided firing mechanism for automatic firearms for firing single shots or a series of shots, wherein the trigger comprises a rod or member mounted 20 in a casing in such a manner as to be displaceable longitudinally and rotatable, the longitudinal displacement of the said rod being utilized to operate a sear to permit firing and the rotary movement being utilized to set the firing mechanism 25 into a position for firing single shots or a series of shots or into a position to lock the said mechanism to prevent firing.

By the provision of a single trigger member according to the present invention for operating the 30 sear during firing as well as for setting and locking the firing mechanism, this mechanism is considerably simplified, which not only facilitates the handling of the firearm, but also increases safety in operation.

In order that the invention may be clearly understood and readily carried into effect reference may now be had to the accompanying drawing illustrating one embodiment thereof by way of example, and in which:

Figure 1 is a longitudinal section showing the trigger casing with the firing mechanism in locked position,

Figure 2 is a similar section showing the mechanism in the released position with the trigger depressed,

Figure 3 is an elevation of the trigger as seen in the direction of the arrow s,

Figure 4 is a fragmentary section on the line IV—IV of Fig. 2, as seen in a direction from right to left, with the trigger removed,

Figure 5 shows a detail of the setting means for the trigger, and

Figure 6 is a plan view of the trigger press button.

Referring to the drawing, 1 indicates the casing

of the firing mechanism. The said casing may be provided with a pistol grip or handles according to how the arm is to be used, but these are not shown. The firing mechanism proper comprises the sear, which co-operates with the locking mechanism, and the member which performs various kinds of movement and operates the sear during firing if set in a certain manner. This member forms the trigger proper of the mechanism and comprises a rod 5 mounted in bearings 2, 3 formed in the casing 1. At one end, the rod 5 is provided with an enlarged cylindrical head 6, which is mounted in a bearing 4 of the casing 1. The enlarged head forms a press button for facilitating the operation of the trigger. At the other end, the rod 5 is rounded at 7, and this rounded end co-operates with the arm 8 of the sear which is rockably mounted on a pin 9. The other arm 10 of the sear coacts with a spring 13 which urges its outer end into the recoil path of the breech mechanism. In the example shown, this mechanism comprises a breech block carrier 12, with a projection 11 with which the arm 10 of the sear co-operates.

According to the invention, the trigger 5 is provided with means for setting and locking the mechanism for firing single shots or a series of shots and for locking the mechanism for preventing firing.

For setting the firing mechanism, there is provided an arrangement x (Figure 6), which consists of a recess on the periphery of the cylindrical press button 6. The recess is bounded partly by an end face 15 and partly by longitudinal grooves 16, 16', which are formed on the periphery in the direction of the longitudinal axis of the trigger 5. The width of the longitudinal grooves 16, 16' corresponds to the width of a projection 14. The said projection is provided on the bearing 4 and extends into the bore thereof. The press button is furthermore provided with a thumb piece 17 for facilitating the operation of the trigger 5 during the rotary movement thereof. This thumb piece also forms an indicator for indicating the set position of the trigger 5, the positions being marked on the outer surface of the casing 1 by suitable indicia.

Between the bearings 2 and 3, the rod 5 is of rectangular cross section and carries a disc 20 having a long boss 23. The disc 20 is provided with means co-operating with the stationary parts of the firing mechanism and adapted to locate the trigger in set position. This means may comprise a knife-edged radial ridge 26 formed on the face of the disc 20 adjacent the bearing 2

(Figure 5). Radial recesses 27 (Figure 4) are provided on the adjacent end face of the bearing 2, said recesses being spaced through 45° and corresponding in shape to the ridge 26 engaging 5 in them in accordance with the setting. Bearing against the disc 28 is a spring 30 disposed concentrically to the rod 5 and bearing at its other end against a shoulder 28 provided on the rod 5. The spring 30 firstly loads the disc 28, so as to 10 cause engagement of the ridge 26 thereof with the recess 27, secondly it returns the trigger after firing into its initial position, wherein the shoulder 28 is applied to the bearing 3.

In addition to the said positioning means, the 15 disc 20 carries means for co-operating with the sear 10 and forming locking means for the firing mechanism. These means may comprise an arm 21, which co-operates with a projection 22 formed on the arm 10 of the sear.

20 For firing a shot, the marksman presses with his finger upon the press button of the trigger 5, the sliding movement being transmitted to the sear 8 which releases the breech block member 12 and the projection 11 whereof operates the firing pin in known manner.

In the position shown in Figure 1, the firing mechanism is locked, so that no shot can be fired. In the locked position, the projection 14 of the bearing 4 is located opposite the end face 15 (Figures 1 and 6) of the press button 6 and prevents 30 sliding longitudinal movement in the direction of the arrow s. In this position not only the trigger is locked, which is prevented from sliding longitudinal movement, but also the sear, since the arm 21 of the disc 20 is located opposite the projection 22 and thereby prevents the sear from rocking which might occur unintentionally when the gun is shaken. Accidental discharge is thereby prevented. By rotation of the press button 6 40 with the aid of the operating thumb piece 17 to the right or to the left through an angle of 45° (Figure 3) the firing mechanism is set for firing. One position may be for firing single shots and the other for firing a series of shots, it being understood that the firing mechanism is provided 45 with an interrupter for firing single shots, which may be of any known construction and is not shown for this reason. During the rotation of the press button 6, the rectangular portion 25 of the rod carries the disc 20 with it, whereby the 50 ridge 26 is disengaged from the recess 27. During this movement the disc 20 is axially displaced on the trigger rod 5 to an amount corresponding to the height of the ridge 26 and thereby compresses the spring 30. Upon rotation through an 55 angle of 45°, the projection 14 of the bearing abuts against the side of the slot 16 or 16', so that further rotation is prevented and the firing mechanism is set for firing, since the projection or arm 21 of the disc 20 does not oppose the movement of the sear. When the trigger has been set 60 into the corresponding position, the ridge 26 engages in another radial recess 27 on the bearing 2, since it is pressed by the spring 30 acting upon the disc 20, and the mechanism is set for firing. 65 The projection 14 is opposite the slot 16 or 16' of the press button, so that it does not prevent sliding longitudinal movement of the trigger, which is necessary for the operation of the sear 8 during firing.

70 What I claim is:

1. A firing control mechanism for automatic

firearms comprising a casing, a trigger rotatably and slidably mounted in said casing, a sear, a press button on said trigger, a bearing for said press button having a projection and said press button having recesses cooperating with said projection to permit slidable movement of said trigger at only certain predetermined rotary positions thereof and prevent slidable movement of said trigger at other rotary positions thereof. 5

2. A firing control mechanism for automatic 10 firearms comprising a casing, a trigger rotatably and slidably mounted in said casing, a sear, a press button on said trigger, a bearing for said press button having a projection and said press button having recesses cooperating with said projection to permit slidable movement of said trigger at only certain predetermined rotary positions 15 thereof and the end face of said press button being designed to cooperate with said projection to prevent slidable movement of said trigger at 20 other rotary positions thereof.

3. A firing control mechanism for automatic firearms comprising a casing, a trigger rotatably and slidably mounted in said casing, a sear, a disc non-rotatably mounted on said trigger, 25 means on said disc cooperating with said sear for locking the same and means on said disc for fixing said trigger in certain positions to which it may be rotated for controlling the firing.

4. A firing control mechanism for automatic 30 firearms comprising a casing, a trigger rotatably and slidably mounted in said casing, a sear, a disc non-rotatably mounted on said trigger, means on said disc cooperating with said sear for locking the same, a bearing for said trigger having radial 35 slots therein and a radial ridge on said disc co-operating with said slots for fixing the trigger in certain predetermined positions.

5. A firing control mechanism for automatic 40 firearms comprising a casing, a trigger rotatably and slidably mounted in said casing, a sear, a disc non-rotatably mounted on said trigger, means on 45 said disc cooperating with said sear for locking the same, a bearing for said trigger having radial slots therein and a radial ridge on said disc co-operating with said slots for fixing the trigger in certain predetermined positions, and a spring 50 urging said ridge into said slots and returning said trigger to initial position.

6. A firing control mechanism for automatic 55 firearms comprising a casing, a trigger rotatably and slidably mounted in said casing, a sear, a disc non-rotatably mounted on said trigger, means on 60 said disc cooperating with said sear for locking the same, a bearing for said trigger having radial slots therein and a radial ridge on said disc co-operating with said slots for fixing the trigger in certain predetermined positions and a spring 65 urging said ridge into said slots and returning said trigger to initial position, and a second bearing for said trigger limiting the return of said trigger under the influence of said spring.

7. A firing control mechanism for automatic 70 firearms comprising a casing, a trigger rotatably and slidably mounted in said casing, a sear, said sear being pivotally mounted and having a projection thereon, a disc mounted on said trigger and said disc having a projection adapted to co-operate with said projection on said sear in order to prevent pivotal movement of said sear at a predetermined position of said trigger. 75
